(57) CLAIM

The ornamental design for a protective covering for an ear guard, as shown and described.

DESCRIPTION

FIG. 1 is a front view of a protective covering for an ear guard of the present invention;

FIG. 2 is a bottom plan view of the protective covering;

FIG. 3 is a top plan view of the protective covering;

FIG. 4 is a rear plan view of the protective covering;

FIG. 5 is a right side plan view of the protective covering; and,

FIG. 6 is a left side plan view of the protective covering.

The broken lines showing “fasteners” and the backing are for environmental purposes only and form no part of the claimed design.
